UNITED STATES PATENT OFFICE.

THOMAS JEFFERSON BULLOCK, OF FREEDOM, KENTUCKY.

WHIFFLETREE-CLIP.

SPECIFICATION forming part of Letters Patent No. 738,405, dated September 8, 1903.

Application filed May 9, 1903. Serial No. 156,458. (No model.)

To all whom it may concern:

Be it known that I, THOMAS JEFFERSON BULLOCK, a citizen of the United States, residing at Freedom, in the county of Barren and State 5 of Kentucky, have invented a new and useful Whiffletree-Clip, of which the following is a specification.

This invention is a whiffletree-clip designed to connect the loop - ring to the end of the 10 whiffletree; and the object of the invention is to provide a clip of this kind which can be easily and quickly connected to any of the whiffletrees now in use; and with this object in view this invention consists, essentially, of 15 two plates hinged together at their rear ends, each plate being provided with barbs adapted to bind into the upper and lower faces of the whiffletree, one of the plates having a boss at the forward end against which the lap-ring 20 bears, and means for fastening the clip-plates together.

The invention consists also in certain details of construction and novelties of combination, all of which will be fully described hereinafter 25 and pointed out in the claims.

In the drawings forming part of this specification, Figure 1 is a perspective view showing the practical application of my invention. Fig. 2 is a view showing the clip disconnected 30 from the end of the whiffletree. Fig. 3 is a vertical longitudinal sectional view of said clip, showing the position the various parts assume when the clip is connected to the end of the whiffletree.

35 In carrying out my invention I employ two plates A and B, which are connected at their rear ends by means of a hinged joint C. These plates are broader at their rear ends than at the forward ends, and adjacent to their 40 rear ends they are bowed or curved, as shown at A' and B', said bowed or curved portions being provided with inwardly - projecting barbs D, which are adapted to bite into the end of the whiffletree E. The forward end of 45 the plate B is formed with a cylindrical boss F, which has a central squared portion G upon the upper end thereof, and passing upwardly through said boss is the bolt H. The forward end of the plate A has a square opening I,

which is adapted to fit over the squared portion G of the boss F, and the nut K is screwed upon the end of the bolt H for the purpose of fastening the said forward ends of the plates together. The eye of the lap-ring L is passed over the boss F before the forward ends of the 50 plates are connected, and the inner face of the boss is curved or cut away, as shown at F', to provide a suitable bearing for the eye of said lap-ring. In order to tightly bind the plates upon the end of the whiffletree, the bolt M, 55 which passes upwardly through the bottom plate B and also through the top plate A, has a nut N screwed thereon.

It will be noted that the upper face of both nuts K and N are slotted, so that a screw-driver 60 can be utilized for turning them, thereby avoiding the necessity of employing a wrench.

It will thus be seen that I provide an exceedingly cheap, simple, and efficient construction of whiffletree-clip by means of which 70 the ordinary construction of lap-ring can be connected to the end of the whiffletree.

Having thus fully described my invention, what I claim as new, and desire to secure by Letters Patent, is—

75 1. A clip comprising two hinged plates adapted to fit over and extend in advance of a whiffletree, said plates having perforations in vertical alinement intermediate their ends, one of said plates having a boss formed on its forward end, and the other plate having an eye adapted to fit over said boss, means for locking the eye on the boss, a bolt adapted to pass through and project from the alining perforations, and a nut adapted to be secured on 80 the projecting end of said bolt.

2. A device of the kind described comprising hinged plates adapted to fit over a whiffletree, a boss formed on the lower plate adjacent its forward end, said boss being recessed 90 on its inner face, a lap - ring having an eye adapted to fit over the boss and engage the recessed portion of same, and means for locking the upper plate to the boss.

THOMAS JEFFERSON BULLOCK.
